UNITED STATES PATENT OFFICE.

CHARLES H. COCHRANE, OF CHICAGO, ILLINOIS.

PLATEN PRINTING PRESS.

Application filed January 9, 1925. Serial No. 1,400.

My invention relates particularly to oscillating platen printing presses although not limited to this use alone, and involves mechanism for conveying successively sheets to the platen for printing and after printing conveying the sheets from the platen, the general object of the invention residing in the provision of a mechanism of this character which is simple, efficient and well adapted for relatively great operating speeds all with a view toward effecting an increased speed of the printing press with consequent decrease in the time required for the printing operation.

With this object in view my invention consists in certain features of novelty in the construction, combination, and arrangement of parts by which the said object and certain other objects, hereinafter appearing, are effected, all as fully described with reference to the accompanying drawings and more particularly pointed out in the appended claims.

In the said drawings—

Figure 1 is a partial side elevation of an oscillating platen printing press embodying my invention.

Figure 2 is a partial top plan view of the same.

Figure 3 is a partial section on the line 3—3 of Fig. 1.

Figures 4, 5, and 6 are enlarged partial views in side elevation showing certain portions of the mechanism as hereinafter described.

Figure 7 is an enlarged partial section in side elevation showing certain portions of the mechanism as hereinafter described.

Figure 8 is a partial enlarged front elevation of the mechanism shown in Figure 7.

Figure 9 is an enlarged partial view in side elevation showing another portion of the mechanism as hereinafter described.

Figures 10 and 11 are respectively enlarged partial side and rear elevations of a portion of the mechanism as hereinafter described.

Like characters of reference indicate like parts in the various views.

Referring to the drawings a horizontal crank shaft 1 extends across between and is revolvably mounted in journals in spaced side frames 2 of the press, and a second horizontal shaft 3 disposed below and some distance to the rear of the shaft 1 extends across between the side frames 2 and is also revolvably

mounted in journals in the side frames. A forwardly facing platen 4, disposed between the side frames, is provided with a pair of downwardly extending arms 5 which are pivoted at their lower ends on the axis of the shaft 3 by means of inwardly extending bored bosses 6 on the side frames 2 surrounding the shaft 3 and engaging bores in the arms 5. See Figs. 1, 2, and 3. The platen is thus mounted for oscillating movement on a horizontal axis disposed below the same, and is oscillated to and away from a stationary rearwardly facing form 7, secured between the side frames 2 in a suitable manner, as follows. The crank shaft 1 extends outwardly of each side frame 2, and secured on respective ends of this shaft in a common radial plane is a pair of cranks 8. A transverse shaft 9 is secured to the platen at the rear thereof, and connecting bars 11 are pivotally mounted at respective ends to the cranks and shaft 9 whereby upon rotation of the crank shaft 1 the platen is oscillated to and from the form 7 for periodically effecting impression on the form.

The form is inked during operation of the press by means of inking rollers 12 mounted on a pair of carriages 13 revolvably mounted on the axis of the crank shaft 1 and disposed at respective sides of the form, the rollers being spring pressed inwardly and stationary bearers 14 being provided on either side of the form for positioning the rollers. The carriages 13 are rotated from a common driving member at the front of the press, not shown, by means of identical gear trains 15 disposed between respective carriages and side frames 2 whereby the rollers 12 transfer the ink from a suitable source, not shown, to the form.

The crank shaft 1 is driven from the aforementioned driving member by means of a gear train 16 disposed between one of the cranks 8 and a side frame 2 whereby the inking rollers 12 are rotated about the form in timed relation with the oscillation of the platen, the inking rollers passing over the form while the platen is separated from the form.

As usual a sheet clamp 17 is provided which is pivoted on the axis of the platen and shaft 3 by reason of the lower end thereof being journaled on the bosses 6. The sheet clamp extends upwardly from the shaft 3 and its upper end which overlies the platen is, as usual, in the form of a pair of

transversely spaced clamp fingers which are disposed at respective sides of the type or plate portion of the form for clamping the side edge portions of a sheet against the platen and stripping the sheet off the form after an impression is made thereon. A compression spring device 18 is engaged with a downwardly extending arm 19 of the sheet clamp and spring presses the sheet clamp in a direction toward the platen.

A gear 21 is revolvably mounted, by means of a transverse shaft 22 mounted on the side frames 2 below the shaft 1, and is the same diameter as and meshes with the gear of the gear train 16 which is secured on the shaft 1 for driving the same. Secured with the gear 21 for rotation therewith is a cam 23, and a lever 24, pivotally mounted at an intermediate point thereon on the adjacent side frame 2, is actuated at its upper end by the cam 23. A connecting rod 25 has its respective ends pivotally connected to the lower end of the lever 24 and the arm 19 whereby the cam 23 actuates the sheet clamp 17 against the influence of the spring device 18 in a manner hereinafter referred to.

A feed board 26 is disposed above the platen at the rear portion of the press and is provided as usual with a side register guide 27 and front register drop guides 28 which are secured on a transverse pivotally mounted shaft 29 whereby these drop guides can be raised to permit the sheets to be moved forwardly off the feed board after registry. The front register guides are spaced to engage the leading edge of a sheet 31 on the feed board adjacent respective sides thereof and cooperate with usual extensions 32 on the front end of the feed board, see Fig. 4, to register the sheets with the leading edges thereof projecting a short distance forwardly of the front of the feed board in order to permit gripping of the registered sheets as hereinafter described.

Another cam 33 is secured with the aforementioned gear 21 for rotation therewith. A lever 34 is pivotally mounted at an intermediate point thereon on the side frame 2 adjacent the cam 33 and is actuated at one end by the cam 33. A connecting bar 35 is pivotally connected at opposite ends thereof to the other end of the lever 34 and to an arm 36 secured to the shaft 29 whereby the cam 33 actuates the shaft 29 to raise the guides 28 and to permit them to be lowered, a tension spring 37 serving to lower the guides as controlled by this cam.

As hereinbefore mentioned the shaft 3 extends across between the side frames 2 and is disposed coaxially with the pivotal axis of the platen 4 whose arms 5 are journaled on the bosses 6. Secured on this shaft 3 immediately adjacent the inner ends of respective bosses 6 is a pair of identical coaxial sprockets 38 which aline with respective

sides of the platen. Secured to the platen at respective sides of the platen and extending upwardly and rearwardly therefrom is a pair of brackets 39, and disposed at the upper end of the platen and alined with respective sprockets 38 is another pair of identical coaxial sprockets 41 which are revolvably mounted and carried with the platen by means of a transverse shaft 42 journaled in the brackets 39 and upon which the sprockets 41 are secured. Another pair of identical coaxial sprockets 43 alined with respective sprockets 38 are revolvably mounted and carried with the platen to the rear of the sprockets 41 by means of a transverse shaft 44 journaled in slide blocks 45 mounted in slides extending upwardly and rearwardly on respective brackets 39, the slide blocks being yieldably urged upwardly and rearwardly in the slides by compression springs 46 in a usual manner. A pair of brackets 47 are secured to respective arms 5 and extend rearwardly therefrom, and carried by these brackets at their rear ends by means of a transverse shaft 48 journaled in these brackets is another pair of identical coaxial sprockets 49 which are secured to this shaft in alinement with respective sprockets 38. Another pair of brackets 51 are secured to respective arms 5 and extend forwardly therefrom immediately above the sprockets 38, and carried by these brackets at their front ends by means of a stationary transverse shaft 52 secured in these brackets is another pair of identical coaxial sprockets 53 which are revolvably mounted on this shaft in alinement with respective sprockets 38.

A pair of endless chains 54 of equal length are trained over respective alined sprockets 38, 41, 43, and 49 and under respective sprockets 53, and by reason of the transverse disposition of the sprockets the chains are disposed for corresponding lineal closed path movement at respective sides of the platen, the disposition of the sprockets 41 and 53 maintaining the front stretch of the chains in parallelism with the face of the platen.

A plurality of sheet gripping means are mounted on the chains 54 at equally spaced intervals therealong. These gripping means are identical and embody bars 55 secured to the chains and extending therebetween. See particularly Figs. 4, 5, 6, and 9. These bars are of flat form and are disposed in planes parallel with the pitch line of the chains on the outside of the chains so that they will clear the face of the platen at the front stretch of the chains. Secured to the ends of the bars immediately inside of the chains and projecting outwardly from the bars are bearing members 56 in which are journaled gripper shafts 57 which extend transversely in parallelism with the bars and are disposed slightly below the edges of the bars

which face downwardly when the bars are at the front stretch of the chains. Secured at intervals along the gripper shafts between the bearing members 56 are grippers 58 which are adapted to clamp sheets 31 against the outer faces of respective bars 55. Small gears 59 are secured on the ends of the shafts 57, and gear segment portions of levers 61, pivotally mounted at 62 on respective bearings 56, are engaged with the gears 59 for operating the gripper shafts into and out of sheet clamping or gripping position. The levers 61 extend outwardly from their pivotal axes, and tension springs 63 secured 15 to these levers and to respective bars 55 serve to maintain the grippers both in the closed and open positions thereof by reason of their passing over the axis of the levers 61 in the movement of the levers to open or 20 close the grippers. The opening movement of the grippers is limited by projections 64 on the grippers engaging respective bars 55. Figs. 4 and 5 show the grippers in closed position and gripping a sheet 31, and Fig. 25 9 shows the grippers in open position.

The chains 54 are intermittently actuated in one direction, i. e., the direction to move the gripping means downwardly over the face of the platen 4, in timed relation with the press mechanism to convey sheets from the feed board 26 downwardly to the platen for printing and after printing downwardly from the platen for discharge. The means for effecting this intermittent movement of the chains 54 is constructed as follows. See Figs. 1, 2, 10, and 11. The cam gear 21 is provided with an inwardly facing cam groove 65, and the upper end of a lever 66, pivotally mounted at an intermediate point 67 thereon to the adjacent side frame 2, is actuated by this cam groove to oscillate the lever during rotation of this gear. The lower end of the lever 66 is pivotally connected to an upwardly facing rack bar 68 which extends rearwardly therefrom underneath the shaft 3 and is supported therefrom by a slide bearing 69 journaled on this shaft. The rack bar 68 faces upwardly and meshes with a gear 71 journaled on the shaft 3. A bored ratchet wheel 72 is secured with the gear 71, and secured on the shaft 3 adjacent the ratchet wheel is an arm 73 upon which is pivotally mounted a pawl 74 engaging the ratchet wheel and spring pressed against the toothed portion of the ratchet wheel by a spring 75.

Oscillation of the lever 66 by rotation of the cam gear 21 causes reciprocation of the rack bar 68 with consequent oscillation of the gear 71 and ratchet wheel 72. The ratchet wheel 72 and the pawl 74 cooperating therewith serve to rotate the shaft 3 intermittently in one direction during oscillation of the gear 71 and ratchet wheel 72, with consequent movement of the chains 54.

by reason of the sprockets 38 being secured to the shaft 3. The direction of the rotation of the shaft 3 is such as to impart downward movement of the chains at the front stretch thereof with consequent movement of the hereinbefore described gripping means, carried by the chains, downwardly over the face of the platen, and the proportion of the parts is such that each intermittent rotation of the shaft 3 moves the chains the distance between the gripping means. 75

The position of the chains 54 and gripping means thereon during the rest periods of the chains is shown in Figs. 1 and 2, in which one of the gripping means is disposed at the top of the sprockets 41 for gripping a sheet on the feed board 26, in which another gripping means is disposed just below the lower end of the platen for holding a sheet while it is being printed, and in which another gripping means is disposed on the front side of the sprockets 38 for discharging a printed sheet, the remaining gripping means being disposed on the rear stretches of the chains. 80 85 90 95

The cam gear 21 makes one revolution to one revolution of the crank shaft 1 and the cams 23, 33, and cam groove 65 are so arranged and timed with respect to each other and with the cranks 8 that the following co-operative action takes place, the mechanism operating in the direction indicated by the arrows in Fig. 1. 95

The chains 54 are stationary during the printing and remain stationary until the platen has moved rearwardly to the position shown in Figs. 1, 2, and 4. Previous to the rearward movement of the platen into this position a sheet 31 has been registered on the feed board 26 by means of the side guide 27 and the drop guides 28 which have been in their lower position resting on the extensions 32 for this purpose. The grippers 58 of the gripping means at the top of the sprockets 41 have been in open position, and when the bar 55 of this gripping means passes under the leading edge of the sheet, projecting from the front edge of the feed board in registered position as above described, a pair of stationary studs 76 carried on the feed board are engaged by respective levers 61 of this gripping means, and these studs, by reason of the rearward movement of the platen and consequently this gripping means, cause these levers 61 to pivot forwardly from the position shown in dotted lines to the position shown in full lines, thereby causing the grippers 58 to close and grip the sheet 31.

lines in Fig. 4 to the position shown in full lines in this figure to close the grippers and clamp the sheet. Immediately the drop guides 28 are raised by the cam 33, as shown in Fig. 4, and remain raised until this sheet is moved from under these guides, the guides being lowered after the sheet passes beyond the same to register the next sheet. Immediately after the sheet is gripped and the drop 136

guides 28 raised the cam groove 65 operating as hereinbefore described actuates the chains 54 to move the aforementioned gripping means at the top of the sprockets 41 forwardly over the same and downwardly on the front stretch of the chains over the face of the platen, the gripped sheet being drawn over a roller 77 on the shaft 42 and downwardly over the face of the platen. Fig. 5 5 shows a gripping means as it is entered on the front stretch of the chains with a gripped sheet 31 being drawn off of the feed board under the raised drop guides 28. After the sheet is gripped the platen continues to move 10 rearwardly, this being permitted by reason of the gripping means at the top of the sprockets 41 moving as above stated, and then moves forward toward impression. The movement of the chains is continued 15 until the above designated gripping means reaches a position just below the lower edge of the platen in which position the sheet gripped thereby is on the platen in position for printing. In this position the movement 20 of the chains terminates, the succeeding gripping means being then positioned at the top of the sprockets 41 preparatory to gripping the next sheet on the feed board and the drop guides 28 being lowered for the 25 registry of the next sheet immediately after the preceding sheet has passed from under the same. The movement of the chains terminates when the platen is some distance from the form, and the cam 23 actuates the 30 sheet clamp 17 to move forwardly with the platen in spaced relation therewith to clear the gripping means moving over the platen until the movement of the chains terminates after which the sheet clamp clamps the sheet 35 against the platen previous to the impression by means of the spring device 18.

The clamping surface of the sheet clamp 17 extends below the lower edge of the platen and in the movement of the sheet clamp to 40 clamp a sheet on the platen engages the bar of the gripping means positioned just below the platen to move this gripping means rearwardly to aline the lower portion of the gripped sheet on the face of the platen, see 45 Fig. 6, ledges 78 on the sides of the platen which support the chains to prevent the bars 55 from touching the face of the platen being curved rearwardly at the lower end of the platen to permit this movement of the bars 55. It will be observed that the springs 46 50 operating on the slide blocks 45 serve to maintain the chains taut and permit this movement of the bars 55.

In order to register the gripping means 60 while gripping a sheet in position for printing the sheet clamp 17 is provided with laterally spaced formations 79 adapted to engage the gripper shaft 57 of the gripping means at the lower end of the platen to register the 65 gripping means lineally of its movement

with clamping movement of the sheet clamp, and pairs of laterally spaced blocks 81 are secured on the outer surfaces of the bars 55 and are adapted when respective bars 55 are positioned at the lower end of the platen to 70 oppositely engage the sheet clamp 17 with clamping movement of the sheet clamp to laterally register the bars 55. See Figs. 1, 2, 7, and 8. Thus with clamping movement of the sheet clamp 17 each gripping means gripping a sheet in position for printing is registered so that accurate registry is assured, the sheets being registered as gripped by the gripping means, and the gripping means being then registered while gripping the 75 sheets in position for printing.

After the sheet on the platen is clamped by the sheet clamp 17, further forward movement of the platen effects the impression of the sheet on the inked form 7. After the 80 sheet is printed the platen again moves rearwardly away from the form the sheet clamp serving to strip the sheet from the form. After stripping the sheet from the form the cam 23 separates the sheet clamp from the 85 platen thus releasing the printed sheet and the gripping means gripping the printed sheet. The platen then continues to move rearwardly until it again reaches the position shown in Figs. 1, 2, and 4 when the next 90 sheet registered on the feed board is gripped by the succeeding gripping means at the top of the sprockets 41 in the same manner as before described.

The next intermittent movement of the 95 chains 54 is initiated immediately as the gripping means at the top of the sprockets 41 100 grips a sheet on the feed board 26 and the drop guides are raised as before described, and in this next movement as the gripping means at the top of the sprockets moves 105 downwardly over the platen and carries the next sheet to the platen for printing, the gripping means at the lower edge of the platen and gripping the previously printed sheet moves downwardly and carries the printed sheet with it between suitable sheet 110 guides 82 carried with the platen. As the movement of the chains reaches its end the gripping means gripping the printed sheet 115 is positioned on the front side of the sprockets 38 and is actuated to open the grippers thereof and release the printed sheet by stationary studs 83, carried by the side 120 frames 2, by reason of the movement of the chains causing the levers 61 to engage these studs to operate the same to open the grippers, the levers 61 passing under these studs in further movement of the chains. See Fig. 125 9. Thus the printed sheet is released for discharge. A drum 84 secured to the shaft 3 between the sprockets 38 serves to project the leading edge of the released sheet forwardly and tangentially with respect to the sprockets 130 38 and to engage the sheet with stationary

guides 85 which guide the sheet forwardly upon horizontal conveyor tapes 86 supported on pulleys 87 secured on transverse shafts 88 journaled in the side frames 2 and driven by a gear train 89 driven from the cam gear 21. These tapes as driven carry the printed sheets forwardly for delivery in a suitable manner. Top tapes 91 supported on pulleys 92 secured on transverse shafts 93 journaled in the side frames 2 and also driven by the gear train 89 serve to prevent the sheets from curling up on the tapes 86. It will be observed that the printed sheets are conveyed from the gripping means printed side up thus affording convenient inspection of the product during operation of the press.

In the operation of the press each gripping means in turn is positioned at the top of the sprockets 41 and gripping a sheet on the feed board carries it to the platen for printing and after printing conveys the printed sheet away from the platen for discharge as is obvious.

The successive feeding of the sheets in registry to the gripping means for conveyance to position for printing may be either effected by hand or by any suitable feeding machine as is obvious though the employment of a feeding machine is preferred by reason of it being capable of feeding at high speed.

While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:

1. In an oscillating platen printing press having the platen thereof mounted for pivotal movement on a horizontal axis disposed below the same the combination of sheet carrying means carried with the platen, means operated by and in timed relation with the press mechanism for operating said carrying means intermittently in one direction in a closed path about the platen and downwardly over the face thereof for conveying successively sheets downwardly to the platen for printing and after printing downwardly from the platen for discharge, means for feeding successively sheets in registry to said carrying means above the platen for conveyance of the sheets to the platen, and means for conveying the printed sheets from said carrying means below the platen for delivery.

2. In an oscillating platen printing press having the platen thereof mounted for pivotal movement on a horizontal axis disposed below the same the combination of sheet carrying means carried with the platen, means operated by and in timed relation with

the press mechanism for operating said carrying means intermittently in one direction in a closed path about the platen and downwardly over the face thereof for conveying successively sheets downwardly to the platen for printing and after printing downwardly from the platen for discharge, a feed board for feeding successively sheets in registry to said carrying means above the platen for conveyance of the sheets to the platen, and a sheet conveyor adapted for conveying the sheets printed side up from said carrying means below the platen for delivery.

3. In an oscillating platen printing press the combination of a plurality of sheet gripping means, a flexible endless carrier upon which said gripping means are mounted at equally spaced intervals therealong, means supporting said carrier for lineal closed path movement for effecting a closed path movement of said gripping means about the platen of the press including a toothed revoluble member mounted on the pivotal axis of the platen for driving the carrier and a second revoluble member carried with the platen adjacent its outer end, means timed and operated with the press mechanism for intermittently rotating said first mentioned revoluble member in one direction for effecting intermittent movement of the gripping means for conveying successively sheets gripped by said gripping means to the platen for printing and after printing from the platen for discharge, and means for actuating said gripping means at respective points in the path thereof to grip the sheets and to release the same for discharge.

4. In an oscillating platen printing press having the platen thereof mounted for pivotal movement on a horizontal axis disposed below the same the combination of a pair of endless chains of equal length, a plurality of gripping means mounted on said chains at equally spaced intervals therealong and including bars secured to the chains and extending therebetween, means supporting the chains for lineal closed path movement in corresponding closed paths at respective sides of the platen for effecting a closed path of movement of said gripping means about the platen including a pair of coaxial sprockets secured together and rotatably mounted on the pivotal axis of the platen and a second pair of coaxial sprockets carried with the platen at its upper end, means timed with and operated by the press mechanism for intermittently rotating said first mentioned pair of sprockets in the direction to effect downward movement of the gripping means over the face of the platen for conveying successively sheets gripped by said gripping means to the platen for printing and after printing from the platen for discharge, and means

- for actuating said gripping means to grip the sheets adjacent the upper end of the platen and to release the same below the platen for discharge.
5. In a platen printing press the combination of sheet carrying means, means for operating said carrying means in timed relation with the press mechanism intermittently for conveying successively sheets to 10 position for printing and after printing from said position for discharge, means for feeding successively sheets in registry to said carrying means for conveyance to printing position, and means for registering said carrying means at said position for printing as and for the purpose described.
6. In a platen printing press provided with a sheet clamp operating to clamp a 20 sheet on the platen prior to and to release same after the printing thereof the combination of sheet carrying means, means operated by and in timed relation with the press mechanism for operating said carrying means intermittently in one direction in a closed path about the platen and downwardly over the face thereof for conveying successively sheets to the platen for printing and after printing from the platen for 30 discharge, means for feeding successively sheets in registry to said gripping means for conveyance to the platen, and means associated and operated with said clamp for registering said carrying means at said position for printing as and for the purpose described.
7. In a platen printing press the combination of a plurality of sheet gripping means, means for operating said gripping means in timed relation with the press mechanism intermittently in one direction and in succession in a closed path for conveying successively sheets to position for printing and after printing away from said 40 position for discharge, means for feeding successively sheets in registry to said gripping means for conveyance to printing position, means for actuating said gripping means at respective points in the path thereof to grip the sheets and to release the same for discharge, and means for registering each gripping means while gripping a sheet in position for printing.
8. In a platen printing press provided 50 with a sheet clamp operating to clamp a sheet on the platen of the press prior to and to release the same after the printing thereof the combination of a plurality of sheet gripping means, means for operating said gripping means in timed relation with the press mechanism intermittently in one direction and in equally spaced succession in a closed path about the platen for conveying sheets successively to the platen for 60 printing and after printing from the platen for discharge, means for feeding successively sheets in registry to said gripping means for conveyance to the platen, means for actuating said gripping means at respective points in the path thereof to grip the sheets and to release the same for discharge, and means carried with the sheet clamp for registering each gripping means while gripping a sheet in position for printing.
9. In an oscillating platen printing press having the platen thereof mounted for pivotal movement on a horizontal axis disposed below the same and provided with a sheet clamp disposed for pivotal movement on the axis of the platen and operating to clamp a sheet on the platen prior to and to release the same after the printing thereof the combination of a plurality of sheet gripping means, an endless carrier upon which said gripping means are mounted at equally spaced intervals therealong and adapted and carried with the platen for lineal closed path movement for effecting closed path movement of said gripping means about the platen and downwardly over the face thereof, means operated by and in timed relation with the press mechanism for effecting intermittent movement of said carrier in the direction to effect downward movement of said gripping means over the platen to convey successively sheets downwardly to the platen for printing and after printing downwardly from the platen for discharge, a feed board for feeding successively sheets in registry to said gripping means above the platen, means for actuating said gripping means at respective points in the path thereof to grip the sheets and to release the same for discharge, and means carried by the sheet clamp for registering with clamping thereof each gripping means while gripping a sheet in position for printing.
10. In an oscillating platen printing press the combination of a flexible endless carrier carried with the platen of the press, means supporting said carrier for lineal closed path movement including a toothed revoluble member disposed on the pivotal axis of the platen and engaged with the carrier for operating the same, and means for rotating said revoluble member intermittently in one direction in timed relation with the press mechanism including a one way automatically engaging rotatory clutch device disposed coaxially with said toothed revoluble member.
11. In an oscillating platen printing press the combination of a flexible endless carrier carried with the platen of the press, means supporting said carrier for lineal closed path movement including a toothed revoluble member disposed on the pivotal axis of the platen and engaged with the carrier for operating the same, a revoluble spur gear dis-

posed on the axis of said revolute member, a one way automatically engaging rotatory clutch connection between said gear and said toothed revolute member, a reciprocable rack meshing with said gear, and a revolute member driven with the press mechanism for reciprocating said rack.

12. In an oscillating platen printing press having the platen thereof mounted for pivotal movement on a horizontal axis disposed below the same the combination of a pair of endless chains of equal length, a plurality of gripping means mounted on said chains at equally spaced intervals therealong and including bars secured to the chains and extending therebetween, means supporting the chains for lineal closed path in corresponding closed paths at respective sides of the platen for effecting a closed path of movement of said gripping means about the platen including a pair of coaxial sprockets secured together and rotatably mounted on the pivotal axis of the platen and a second

pair of coaxial sprockets carried with the platen at its upper end, a revolute spur gear disposed on the axis of said first mentioned pair of sprockets, a one way automatically engaging rotatory toothed clutch connection between said gear and said first mentioned pair of sprockets, a reciprocable rack meshing with said gear, a revolute member driven in timed relation with the press mechanism for reciprocating said rack whereby to effect intermittent movement of said gripping means in one direction in their closed path and downwardly over the face of the platen for conveying successively sheets downwardly to the platen for printing and after printing downwardly from the platen for discharge, and means for actuating said gripping means to grip the sheets adjacent the upper end of the platen and to release the same below the platen for discharge.

In witness whereof I hereunto affix my signature this 5th day of January, 1925.

CHARLES H. COCHRANE.
